3 SHEETS—SHEET 3.

UNITED STATES PATENT OFFICE.

OSCAR STEVENSON, OF RIVER GROVE, ILLINOIS.

FIRE-ESCAPE.

1,169,439.

Specification of Letters Patent. Patented Jan. 25, 1916.

Application filed July 12, 1915. Serial No. 39,347.

To all whom it may concern:

Be it known that I, OSCAR STEVENSON, a citizen of the United States, residing at River Grove, in the county of Cook and State of Illinois, have invented certain new and useful Improvements in Fire-Escapes, of which the following is a specification. This invention relates to improvements in life saving apparatus and more particularly to portable fire escapes; and it has for its object to provide a strong, durable and efficient device of this class whereby the inmates of the upper stories of burning buildings may be safely lowered to the ground.

Another object is to provide a portable fire escape comprising an incased reel whereon a cable is wound that, as the reel descends, is paid out through the top of the casing and passes about a sheave which is incased and provided with adjustable governors that bear directly upon the cable; said sheave casing being further provided with manually operable governors disposed in a plane at right angles to the plane of the adjustable governors and that bear directly upon the sheave, the purpose of both governors being to regulate the speed at which the descent is made.

With the foregoing and other objects in view the invention consists in the combination and arrangement of parts to be hereininafter fully described in the following specification, pointed out in the claims and illustrated in the accompanying drawings which form a part of said specification and in which—

Figure 1 is a side elevation of my improved fire escape. Fig. 2 is a sectional view taken on line 2—2 of Fig. 4 showing the interior of the sheave casing. Fig. 3 is a side view of Fig. 2. Fig. 4 is an enlarged view of the upper portion of Fig. 1. Fig. 5 is a side elevation of the reel casing. Fig. 6 is a vertical sectional view taken on line 6—6 of Fig. 5. Fig. 7 is a top plan view of Fig. 5. Fig. 8 is a cross section taken on line 8—8 of Fig. 4.

Like reference characters indicate corresponding parts throughout the several views. The reference numeral 1 denotes the reel casing which is provided with oppositely disposed hooks 2 to which snap hooks 3 are secured that carry the body strap 4 in which the operator may sit and which is adjustable, as shown, to a variety of sizes. The reel casing is provided with the transverse

shaft 5 on which the reel 6 is made fast and said shaft 5 is provided with the handle 7 by which it may be rotated. The casing 1 is formed with an opening or mouth 8 and 60 with parallel lips 9 connected by transverse guide pins 10 and between said pins and lips and into the casing the cable 11 extends which at one end is secured to the reel 6. The said cable extends from the reel casing 65 up through a perforation in one end of one of the hand rods 12, 13 and between a pair of rotary guides 14, 14 carried by projections 15, 15 of the sheave casing 16 and once about the sheave 17 mounted in said casing 70 upon a transverse shaft 18 and out between rotary guides 19 retained in another projection 20 of the said sheave casing and at its free end is provided with the hook or eye 21 adapted for engagement with a suitable hook carried by the building or window casing from which the apparatus is to be suspended for operation.

The reel casing aforesaid is supported by a strap 22 and snap hook 23 in engagement 80 with a hook 24 carried by said casing, said strap 22 being in engagement with an eye 25 formed terminally upon the rod 13. The said hand rods 12, 13 are connected by pivotal links 26 which carry a link 27 to which 85 a snap hook 28 is secured that carries an adjustable strap 29 in which the operator may rest his feet as he sits in the strap 4 and descends.

Referring again to the hand rods 12, 13 90 they are terminally connected to the sheave shaft 18 and bulged outwardly below the same and formed with elongated apertures 30 through which bolts 31 pass into brake shoes 32 which are controlled thereby and 95 which are slidably disposed in angular guides 33 secured to the sheave casing, said brake shoes bearing directly upon the sheave 17. Springs 34 encircling the bolts 31 bear against the hand rods 12, 13 and against the 100 brake shoes 32 to retain the latter in frictional engagement with said sheave. To increase the friction of the brake shoes upon said sheave the operator may manually press the hand rods 12, 13 toward each 105 other in the plane of the bolts 31.

The sheave casing 16 is provided, further, with brackets 35, 35 formed with elongated apertures 36 in alignment with similar apertures in the casing and through the same 110 the terminally threaded bolts 37 pass that are provided with nuts 38, said bolts 37,

- 2
- further, carrying one end of bolts 39 that also pass through perforations in the brackets 35 and that are provided upon their free ends with nuts 40 between which and 5 said brackets 35 and about said bolts springs 41 are disposed. Directly opposite the bolts 37 similar bolts 37' are carried by the sheave casing and side bolts carry similar bolts 39' that pass through brackets 35', the entire 10 construction and arrangement just described being repeated upon the opposite side of the sheave. The bolts 37, 37' carry rotary brake shoes 42 which bear directly upon the cable 11 and press the same against the sheave to regulate the movement of the same. To increase the tension of the members 42 upon the cable the nuts 40, 40' are moved inwardly upon their bolts thus compressing the springs 41, 41' and drawing 15 the bolts 37, 37' toward the sheave.
- In use the operator secures the loop 21 to a suitable hook provided upon or about the window casing and swings the apparatus out of the window; he has previously adjusted 20 the rotary shoes 42 as desired. With one hand upon the rods in the plane of the bolts 31 he takes his seat in the strap 4 and places his feet in the strap 29. His weight will cause the cable to unwind from the reel 6 25 and the rate of his descent will be regulated at will by manual pressure upon the hand rods as previously described.
- When once used the cable is wound again upon the reel by means of the handle 7 and 30 the device is ready for use again.
- What is claimed is:—
1. In a fire escape, an incased shafted reel provided with a handle, an incased sheave, connection between said reel and sheave, 35 hand rods carried by said sheave, connection between said hand rods, a strap carried by said hand rod connection, a seat strap carried by said reel casing and oppositely disposed brake shoes operatively connected 40 to said hand rods and having a bearing upon said sheave.
  2. In a fire escape, an incased shafted reel provided with a handle, an incased sheave, connection between said reel and sheave including 45 a cable, brake shoes carried by said sheave casing and having a bearing upon said sheave, means yieldingly retaining said
- brake shoes in operative relation, manually operable means carried by said sheave casing for increasing the friction of said brake 55 shoes upon said sheave, a strap carried by the last named means and a seat strap carried by the said reel casing.
3. In a fire escape, an incased sheave, an incased reel carried thereby, a cable connecting said reel and sheave, brake shoes carried by said sheave casing for engagement with said sheave and being disposed in a plane at right angles to the plane of rotation of said sheave, manually operable governors 60 for said brake shoes, a strap carried by said governors, a seat strap carried by said reel casing and adjustable rotary brake shoes carried by said sheave casing for engagement with said sheave and disposed in the 65 plane of rotation of the same.
4. In a fire escape, an incased sheave, an incased reel carried thereby, a cable connecting said reel and sheave, rotary brake shoes carried by said sheave casing and 70 bearing upon said cable to press the same against said sheave, means carried by said sheave casing and associated with said rotary brake shoes for regulating the tension of the same upon said cable, hand rods 75 carried by said sheave casing, brake shoes carried and operable by said hand rods and in engagement with said sheave, connection between said hand rods, a strap carried by said connection and a seat strap carried by 80 said reel casing.
5. In a fire escape comprising an incased sheave and a cable passing thereover, bolts movably carried by said sheave casing, 85 rotary brake shoes carried by said bolts in engagement with said cable and adjusting means for said bolts carried by said sheave casing and including spring pressed bolts terminally connected to the first named 90 bolts.
- In testimony that I claim the foregoing as my own I have hereto affixed my signature in the presence of two subscribing witnesses.

OSCAR STEVENSON.
